UNITED STATES PATENT OFFICE.

GEORGE W. J. CRABB, OF NEWARK, AND EDWARD J. RENNIE, OF BLOOMFIELD, NEW JERSEY.

DIRIGIBLE HEADLIGHT.

1,392,747.

Specification of Letters Patent.

Patented Oct. 4, 1921.

Application filed April 26, 1920. Serial No. 376,743.

To all whom it may concern:

Be it known that we, GEORGE W. J. CRABB and EDWARD J. RENNIE, both citizens of the United States, and residents, respectively, of Newark, in the county of Essex and State of New Jersey, and Bloomfield, in the county of Essex and State of New Jersey, have invented a new and Improved 5 Dirigible Headlight, of which the following 10 is a full, clear, and exact description.

This invention relates to head lights and more particularly to the class of head lights of the dirigible type, the same being in the nature of an improvement over a similar 15 invention covered by United States Patent #1,318,973, patented October 14th, 1919.

In said patent, the vertical telescopic standards which support the head lights were respectively connected to the body of 20 the vehicle and the axle, one of said standards being provided with a joint to compensate for relative movements between the axle and the body. One disadvantage incident to such an arrangement is due to the 25 vibration transmitted to the lamp filaments.

It is therefore one of the principal objects of the present invention to provide means for dirigibly associating a head light with a vehicle of the character described, which 30 overcomes the above recited objection by reducing vibrations of the head light to a minimum.

In the motor vehicles of standard construction, the steering mechanism is so arranged that the front wheels are parallel 35 when the car is running straight ahead, but causes them to stand at an angle with respect to each other when making a turn. Where the head lights are individually operated from each steering knuckle, the normal adjustment of the head lights for concentrating the light rays on a single point is destroyed in making a turn. Another 40 object therefore, of the present invention is to provide means for dirigibly associating head lights with the vehicle of this character, which eliminates the above recited objection by the provision of means which turns the head lights an equal degree in order 45 to maintain the concentration of the rays.

Another object of the invention is to provide a dirigible head light, which is capable of vertical adjustments, in order that the

same may be applicable to vehicles of various sizes.

With the above recited and other objects in view, some of which will be more apparent hereafter, reference is made to the following description, claims and accompanying drawings forming a part of this application and in which—

Figure 1 is a fragmentary front elevation of an automobile, illustrating the invention applied thereto, parts being shown in section 65 to disclose the underlying structure.

Fig. 2 is a fragmentary plan view thereof.

Fig. 3 is a detail vertical sectional view taken approximately on the line 3—3 of Fig. 1.

Fig. 4 is a fragmentary detail view of a modified form of the invention.

Referring to the drawings by characters of reference, C designates the chassis or frame of a motor vehicle, A the front axle thereof, which is provided with the usual steering knuckles K at its opposite ends. The steering knuckles K are provided with the usual steering knuckle arms B which are connected by means of the tie rod T whereby the steering wheels W are simultaneously turned by the steering gear.

The invention, which is a means for dirigibly associating the head lights L with the vehicle, includes the bearing sleeves 10, 85 of which there are preferably two. The bearing sleeves 10 are supported from the opposite side channel bars of the chassis in any suitable manner, but are here illustrated as provided with threaded studs 11 passed 90 through openings therein and secured by the clamping nuts 12 disposed at the opposite sides thereof. A second bearing sleeve 13 having an annular boss 14 is arranged in superposed relation to the bearing 95 sleeve 10 and is supported from an angular brace rod 15 bolted as at 16 to the upper face of the side channel bars. The free upper end of the brace rod 15 is apertured for the reception of the shank 17 of a forked 100 or bifurcated member 18, which embraces the annular boss 14 and is secured thereto at diametrically opposite points. The bosses 14 of the sleeves 13 disposed at the opposite sides of the vehicle are preferably connected 105 by a transversely extending brace rod 19. Vertically aligned shaft sections 20 and 21 are provided and connected by a universal

joint 22, the lowermost shaft section bearing in the sleeve 10. The uppermost shaft section 21 is provided with a detachable thimble 23 having its open end threadedly engaged with the upper extremity of said upper shaft section. The closed end of said thimble is provided with a polygonal opening 24. The thimble 23 is designed to be received by and operate in the sleeve 13. 10 The upper end of the sleeve 13 is closed by a cap 25 threaded thereon and provided with an axial opening for the reception of the shank 26 of the head light bracket 27 which is swiveled therein. The lower free 15 extremity 28 of the shank 26 is polygonal and is received by the opening 24 in the thimble. By this arrangement it will be seen that the sleeve 13 may be vertically adjusted with respect to the sleeve 10 without 20 affecting the operative association of the head light bracket with the shaft sections and thimble. The lower extremity of each lower shaft section is provided with a rearwardly disposed radial crank arm 29 25 secured thereto and said crank arms are coupled by means of a connecting rod 30.

The connecting rod 30 is provided with a centrally arranged enlargement 31 having a vertical elongated slot 32. The tie rod T 30 is provided with a forwardly projecting arm 33 having an upturned outer extremity 34 received by the slot 32. By this arrangement the tie rod T and the connecting rod 30 are coupled for simultaneous movement, 35 said coupling constituting a compensating device which allows for the relative vertical movements between the chassis and the axle and the parts connected therewith.

In operation of the device, when the tie 40 rod T is shifted to the right for example, the engagement of the upturned extremity 34 of the arm 33 with the slot 32 of the enlargement 31 will effect a similar simultaneous movement of the connecting rod 30. 45 The movement of the tie rod T to the right effects a turning of the steering wheels to the left through the medium of the steering knuckles. The corresponding movement of the connecting rod 30 rotates the shaft sections 20 and 21 and the thimble 23 to the left, thereby turning the head light bracket 27 in a corresponding direction. The rays of light from the head lights will be simultaneously projected in the direction of 50 travel of the vehicle at all times. The universal joint 22 compensates for any lost motion due to vibration from the co-acting engagement of the arm 33 and enlargement 31, transmitted through the connecting rod 30 55 to the shaft sections. Likewise the free vertical movement of the thimble in the sleeve 13 compensates for vertical movement of the shaft sections due to unusual road shocks.

In the modified form illustrated in Fig. 4 60 of the drawings, in lieu of the enlarged

slotted portion 31 a rectangular frame 40 is provided and the connecting rod 30^a is formed in two sections each threaded into the exterior bosses 41 in the frame. Channeled liners 42 are arranged at the opposite 70 interior longitudinal side edges of the frame and the same are normally forced toward the upturned end of the arm 34 under the action of the springs 43 disposed between each channelled liner 42 and the inner sides of 75 the frame. By such an arrangement, the constant vibration which would be normally transmitted through the shaft sections to the lamp are absorbed by the springs.

While there has been illustrated and described a single and preferred embodiment of the invention, no limitation is made to the precise details of construction but it is understood that variations and modifications which fall within the scope of the appended claims may be resorted to when found expedient.

Having thus described our invention, what we claim as new and desire to secure by Letters Patent, is:—

1. In a dirigible headlight for vehicles, the combination with the chassis, of a sleeve secured to the side bar of the chassis, a rod secured to the said side bar, a second sleeve having its upper end closed by an apertured cap, means for pivotally mounting the sleeve on the upper end of the rod in alinement with the first sleeve, shaft sections connected together by a universal joint, the lower shaft section extending through the first sleeve and provided with a crank arm at its end, a thimble detachably secured to the upper shaft section and slidable in the second sleeve, the upper closed end of the thimble being provided with a polygonal opening, and a headlight bracket having a shank, the lower end of which is polygonal and extends through the openings of the sleeve and thimble.

2. In a dirigible headlight for vehicles, the combination with the chassis, the steering knuckle, and rod secured to the knuckle, of a sleeve carried by the chassis, a second sleeve pivotally supported from the chassis above and in alinement with the first sleeve and having its upper end closed by an apertured cap, shaft sections connected by a universal joint, the lower shaft section extending through the first sleeve and having a crank arm thereon, a thimble secured to the upper shaft section and slidable in the second sleeve, the upper closed end of the thimble having a polygonal opening, a headlight bracket provided with a shank having a polygonal portion, said shank extending through the openings of the sleeve and thimble, and means for operating the crank from the rod connected with the steering knuckle.

GEORGE W. J. CRABB.
